PICTURE AUTOGRAPH BOOK

Annette T. Turpin, Los Angeles, Calif.

Application January 23, 1950, Serial No. 7,434

Term of patent 14 years

(Cl. D6—2)

To all whom it may concern:

Be it known that I, Annette T. Turpin, a citizen of the United States, residing at Los Angeles, in the county of Los Angeles and State of California, have invented a new, original, and ornamental Design for a Picture Autograph Book, of which the following is a specification, reference being had to the accompanying drawing, forming part thereof.

The figure is a perspective view of a picture autograph book, showing my new design, the back covering being plain on the outside.

The essential features of my design reside in the ornamentation shown on the first page thereof.

I claim:

The ornamental design for the picture autograph book, as shown and described.

ANNETTE T. TURPIN.
